EJECTOR PUMP

Martin B. MacNeill and Raymond W. Frank,
Dubuque, Iowa, assignors to A. Y. McDonald
Manufacturing Co., Dubuque, Iowa, a corpora-
tion of Iowa

Application November 13, 1945, Serial No. 628,177

5 Claims. (Cl. 103—5)

1

Our invention relates to a centrifugal pump of the jet variety and has for its primary purpose the provision of a type of pump known as the shallow well jet type and in which access can be had to the inner parts of the pump structure, particularly the jet assembly and the impeller for the removal or replacement of these parts, would it become necessary or desirable after the pump is in operation.

Another and further object of our invention is the provision of a shallow well jet pump which can be easily and quickly converted into a pump of the ordinary centrifugal type and if desired can be converted into a type of pump known as the deep-well jet type variety in which the jet assembly is usually placed in the well or at some remote position away from the pump structure proper.

Another and further object of our invention is the provision of a pump structure which is compact and which can be placed in horizontal positions in use on farms and the like for the purpose of drawing water from wells or for forcing the water into various places, particularly in farming operations as well as in city homes and the like.

Another and further object of our invention is the provision of a shallow well pump which can be easily converted into other types of pumps by an ordinary workman or mechanic without the necessity of having to make major changes in the pump and if desired the operating parts can be sold by a dealer in separate units which can be easily attached to or detached from the pump structure for conversion purposes.

Another and further object of our invention is the provision of a jet pump having a jet assembly located therein which is firmly and easily fixed into the structure and capable of removal therefrom by an ordinary mechanic, made in such manner that it is practically impossible to insert the jet assembly in an improper manner, and which can be easily removed for the insertion of repair parts or for cleanout purposes if desired or necessary.

Another and further object of our invention is the provision of a pump having the jet assembly firmly mounted and supported in the pump structure in such manner that it will not become displaced and which when placed in the structure would not be easily displaced or rendered inoperative by water pressure or the like in the pump housing.

Another and further object of our invention

2

is the provision of a pump having a volute outlet from the impeller chamber and in which a back pressure is minimized from the discharge opening and a minimum of turbulence set up in the main pump chamber as the water is forced out by the impeller into this chamber.

These and other objects will be more fully and better understood by reference to the accompanying sheets of drawings and in which:

Figure 1 is a longitudinal view in elevation of our improved pump showing the motor attached thereto;

Figure 2 is a cross-sectional view on lines 2—2 of Fig. 1, and

Figure 3 is a cross-sectional view on lines 3—3 of Fig. 1.

Referring now specifically to the drawings and in which like reference characters refer to like parts throughout, a pump casing is provided com-

posed of a main rectangular section and a bullet-like section 11 at one side of the said main section, the main section having a rear end wall 12 with a circular opening 13 therein and a trunnion-like extension 14 round the opening 13, the extension

25 having an outer bearing face 15 thereon. A bottom wall 16 is provided having base portions 17, 17 thereon on which the pump structure rests upon any suitable foundation with side walls 18 and 19 which are curved toward each other and

30 merge into a top wall 20 having an internally threaded trunnion 22 thereon to which an outlet pipe 23 is secured. Integrally formed with the side walls 18 and 19, the bottom wall 16 and a vertical front wall 24 is a bullet-shaped extension

35 25 having an opening 26 in the end thereof within which a bushing 27 is threaded with a threaded plug 28 therein, the bushing 27 and the plug 28 forming closure members for the opening 26. The extension 25 has an opening 29 in one side

40 thereof within which an inlet pipe 30 extends which leads to any suitable source of water or other fluids upon which the pump is operating.

An inner wall structure 31 is provided generally boot-shaped in longitudinal section and substantially circular in cross section throughout the greater extent of its length thereby providing an intake chamber 32 inside of the main chamber 33 formed by the outer wall of the pump structure as hereinbefore described. The wall structure 31 has an outflared end portion 34 integrally formed with the main wall structure 31

50 and with the rear end wall 12, the bottom 16 and the side walls 18 and 19, except adjacent the wall 18. An opening 35 is formed from the im-

steller chamber 36, one side of which is formed by the outwardly flared end portion 38 of the wall structure 31. A plate 37 forms a closure for the rear side of the impeller chamber 36, with a flange 38 thereon through which bolts 39 extend into the trunnion like extension 14 on the back plate 12 thereby forming a complete pump housing.

The wall 31 has an opening 40 therein opposite the opening 26 in the end of the extension 25 through which the jet assembly is inserted and removed when desired, the jet assembly comprising a tubular member 41 having a flange 42 thereon to which are secured a plurality of spaced legs 43, 43 which connect with the flange 42 on the tubular member 41 at one of their ends and with a threaded ring 44 at their other ends. The ring 44 is in threaded engagement with the member 31 and has studs 45, 45 for engagement with a suitable wrench whereby the jet assembly can be secured in place in the wall structure 31 and removed therefrom when desired. A jet member 47 is inserted in the ring 44 with a press fit in the ring with its outer end flush with the wall structure 31 and its inner end terminating at the entrance of the Venturi passage in the member 41 which is curved outward at the end of the passage. Extending circumferentially of the wall structure is a flange 48 which supports the inner end of the member 41 with a flange 49 extending around the member 41 and in abutting engagement with the side of the flange 48 whereby the rear end of the tubular member 41 is supported and held in position in the walled structure 31.

An impeller 50 having a hollow hub portion 51 with a renewable seal 52 mounted in the structure 31 is provided having radially extending passages 53, 53 therein extending from the opening in the hollow hub to the outer periphery of the impeller 50, the passages 53 being in communication with the volute discharge passage 36 which extends circumferentially around the periphery of the impeller 50 and which terminates at 54 where it connects with passage 55 formed by the end wall 18 and a wall member 56 integrally formed with the wall 18. The wall member 56 is angularly positioned whereby the passage 55 increases in size toward its discharge end as shown particularly in Fig. 2.

The impeller 50 is mounted upon and supported by a motor shaft 57 having a spring pressed seal 58 therearound to prevent leakage through the opening in the plate 37 through which the motor shaft 57 extends. A motor 59 is provided with which the motor shaft 57 is connected, the motor 59 being secured by means of brackets 60, 60 and a ring 61 to the member 37 which in turn is secured to the main housing as heretofore described.

The operation of the pump as shown and described will be well understood, it is believed, by those skilled in the art. Normally these pumps must be kept primed, that is filled with water or other fluid, or substantially so, before being operated. Drain openings can be provided through which water can be drained if desired to prevent freezing, and if the pump is drained the pump casing must be filled with water, prior to commencement of operation of the pump. Assuming that the casing is filled with water as the motor commences operation, the impeller 50 rotates in a counterclockwise direction thus forcing water out of the passage 53 and building up pressure in the main chamber. As the pressure in the main chamber is built up, water is forced through the jet 47 thereby materially increasing the suc-

tion around the discharge end of the jet 47 and the end of the intake passage in the tube 41 until maximum capacity of the pump is obtained, depending partially upon the speed at which the impeller is rotated. The water is discharged into the volute passage 36 and thence to the passage 55 into the main chamber and a portion discharged through the outlet pipe 23, and another portion passing through the jet 47.

In assembling the pump for the operation described above, the motor 59, the impeller 50 and plate 37 can be assembled as a unit, and placed in position in the main casting and attached to the flange 14 in the main housing by the bolts 39, and detached from the main housing for the purpose of removing any of the parts, bearings or the like for the purpose of renewal, repair, cleaning or the like.

The jet assembly is inserted in the chamber 32 through the opening 26 in the wall 25. The jet 47 is placed in position in the ring 44, the jet 47 being secured in position in the ring 44 by being pressed therein and held in position by a friction fit, and the whole jet assembly including the tube 41 is placed in position with the inner end of the tube 41 supported by the flange 48. The ring 44 is threaded into the wall 31 and a wrench applied to the studs 45 so as to tighten the jet assembly in position. In order to produce the greatest efficiency it is advisable that the inner end of the jet 47 terminate at the entrance of the Venturi passage through the tube 41 which it will be noted is outwardly flared because of the contour of the flange 42. The outer surface of the jet 47 is arcuate so as to provide sufficient space for the free flow of fluid around the jet and to insure the flow of fluid in an axial direction at the entrance of the passage in the tube 41. The bushing 27 with the plug 28 therein is inserted 40 thereby closing the casing and the pump is ready for operation when set up with suitable connections. When it is desired to renew the jet assembly the bushing 27 is removed, access is thereby had to the ring 44, a tool can be applied to the studs 45, the assembly removed for the purpose of repair, cleaning or the like as may be desired.

If it is desired to convert the pump into an ordinary centrifugal pump, the jet assembly is removed as hereinabove described, a plug is threaded into the opening 40 in the casing 31 thereby closing this opening, the bushing 27 with the plug 28 therein in place as shown and the pump operates as an ordinary centrifugal pump with the same inlet and outlet connections.

If it is desired to convert the pump shown and described into a type known as a deep well jet pump, the jet assembly is removed, a plug is threaded into the opening 40 closing the opening 40 the same as heretofore described, the plug 28 is removed from the bushing 27 and a drive pipe connected thereto which leads to a jet assembly in a casing usually positioned in the well with the inlet pipe 30 connected to the jet assembly casing whereby the pipe 30 performs the function of an outlet pipe for the remotely positioned jet assembly casing and an inlet pipe for the pump as described and claimed herein, all of which is well known and understood in the art.

We provide therefore a pump in which all of the interior parts are easily accessible to a person of ordinary skill for replacement and repair and the like. A pump is provided which can be easily and quickly changed to perform a plurality of functions which enables the manufacturer to make fewer models and types, the dealer to carry

less stock, and which can be easily converted by an ordinary person to various uses and purposes.

While we have described more or less precisely the details of construction, we do not wish to be understood as limiting ourselves thereto, as we contemplate changes in form and the proportion of parts and the substitution of equivalents as circumstances may suggest or render expedient without departing from the spirit and scope of our invention.

We claim:

1. A horizontal pump comprising in combination a casing having a projecting portion with an inlet opening in one side thereof and an opening in the end of the said projecting portion and having an outlet opening, the said casing having an inner wall structure formed therewith generally circular in cross section and encompassing the inlet opening and outwardly flared at one of its ends whereby an impeller chamber is formed having a discharge opening into the chamber formed by the casing and having an opening therein in alignment with the opening in the end of the said projecting portion, a jet assembly comprising a tube, a threaded ring spaced from one end of said tube but connected thereto, a jet removably positioned in said ring having its discharge end terminating adjacent the intake end of the said tube, the inner end of the said tube being supported by the inner wall structure and the threaded ring also being in engagement with the inner wall structure, the jet providing a communicating passage from the chamber formed by the casing and the chamber formed by the inner wall structure, a plate removably secured to said casing forming a closure member for one side of the impeller chamber, a rotary impeller having a central intake opening therein in said impeller chamber, and a removable plug in the opening in the end of the projecting portion of the casings the said jet discharging into the said impeller through the said tube, the pump having a flow line from the impeller discharge to the jet nozzle and from the jet discharge to the impeller intake opening.

2. A horizontal pump comprising in combination a casing having a projecting portion with an inlet opening in one side thereof and an opening in the end of the said projecting portion and having an outlet opening, the said casing having an inner wall structure formed therewith generally circular in cross section and encompassing the inlet opening and outwardly flared at one of its ends whereby an impeller chamber is formed having a discharge into the chamber formed by the casing and having an opening therein in alignment with the opening in the end of the said projecting portion, a jet assembly comprising a tube, a threaded ring spaced from one end of said tube but connected thereto, a jet removably positioned in said ring having its discharge end terminating adjacent the intake end of the said tube, the inner end of the said tube being supported by an annular flange on the inner wall structure and the threaded ring also being in engagement with the inner wall structure, the jet providing a communicating passage from the chamber formed by the casing and the chamber formed by the inner wall structure, a plate removably secured to said casing forming a closure member for one side of the impeller chamber, a rotary impeller having a central intake opening therein in said impeller chamber, and a removable plug in the opening in the end of the projection portion of the cas-

ings the said tube forming a discharge for the said jet into the central opening of the impeller, the said pump having a flow line from the impeller discharge to the jet nozzle and from the jet discharge to the impeller intake opening.

3. A horizontal pump comprising in combination a casing having a projecting portion with an inlet opening in one side thereof and an opening in the end of the said projecting portion and having an outlet opening, the said casing having an inner wall structure formed therewith generally circular in cross section and encompassing the inlet opening and outwardly flared at one of its ends whereby an impeller chamber is formed having a discharge opening into the chamber formed by the said casing and having an opening therein in alignment with the opening in the end of the said projecting portion, a jet assembly comprising a tube, a threaded ring spaced from one end of said tube but connected thereto, a jet removably positioned in said ring having its discharge end terminating adjacent the intake end of the said tube, the inner end of the said tube being supported by an annular flange on the inner wall structure and the threaded ring also being in engagement with the inner wall structure, the jet providing a communicating passage from the chamber formed by the casing and the chamber formed by the inner wall structure, a plate removably secured to said casing forming a closure member for one side of the impeller chamber, a rotary impeller having a hollow hub portion surrounded by a removable seal, and a removable plug in the opening in the end of the projecting portion of the casings the said jet discharging through the said tube into the hollow hub of the impeller, the said pump having a flow line from the impeller discharge opening to the jet nozzle and from the jet discharge to the hollow hub portion of said impeller.

4. A pump comprising in combination a main housing and a projecting portion at one side thereof, the main housing having a discharge opening therein, the projecting portion having an intake opening therein and a jet assembly opening in the end thereof, the said main housing and the projecting portion forming a main water chamber, an internal wall section integrally formed with said main housing and said projecting portion extending generally horizontal of the main water chamber and enclosing the intake opening in said projecting portion, having a jet assembly receiving opening therein and outwardly flared at one of its ends whereby an impeller chamber is formed, the impeller chamber having a discharge opening into said main chamber whereby communication is had between said impeller chamber and the main chamber, a rotary impeller having a central intake opening therein in said chamber, a jet assembly including a tube the inner end of which is supported by the internal wall section and having horizontally projecting legs on the opposite end and an externally threaded ring integrally formed with the said legs in threaded engagement with the said internal wall section and a jet having its inner end terminating adjacent the outer end of the said tube mounted in said externally threaded ring, a plate forming a closure member for one side of the impeller chamber and a plug closing the opening in the end of the projecting portion, the said pump having a flow line from the impeller discharge opening to the jet nozzle

7
and from the jet discharge to the central intake opening in the impeller.

5. A pump comprising in combination a main housing and a projecting portion at one side thereof, the main housing having a discharge opening therein, the projecting portion having an intake opening therein and a jet assembly opening in the end thereof, the said main housing and the projecting portion forming a main water chamber, an internal wall section integrally formed with said main housing and said projecting portion extending generally horizontal of the chamber formed by the main housing and enclosing the intake opening in said projecting portion and having a jet assembly receiving opening therein and outwardly flared at one of its ends whereby an impeller chamber is formed having a discharge opening into said main chamber whereby communication is had between said impeller chamber and the main chamber, a rotary impeller in said chamber having a central intake opening therein, a jet assembly including a tube the inner end of which is supported by the internal wall section and in communication with intake opening in said impeller, the said tube having horizontally projecting legs on its opposite end and an externally threaded ring in-

10 tegrally formed with the said legs in threaded engagement with the said internal wall section and a jet mounted in said ring portion the said jet being in communication with the said main water chamber, a plate forming a closure member for one side of the impeller chamber and a plug closing the opening in the end of the projecting portion, the said pump having a flow line from the impeller discharge opening to the jet nozzle and from the jet discharge to the impeller intake opening.
